CAN COVER REPLACER

Norman Gran, Chicago, Ill., assignor to A. H.
Arnold & Company, Chicago, Ill., a corporation
of Illinois

Application August 15, 1941, Serial No. 407,093

7 Claims.

(Cl. 29—84)

The present invention relates in general to improvements in the art of cleansing containers and of reassembling the clean parts, and relates more specifically to various improvements in the construction and operation of mechanism for replacing the covers upon milk cans or the like after the individual parts have been washed and sterilized.

An object of the invention is to provide an improved receptacle cover applying device which is simple in construction and efficient in operation.

It is customary in the dairy industry, to receive fresh milk from the producers in rather large batches ranging in volume from five to ten gallons, each batch being confined in a relatively large milk can sealed with a standard circular cover. When these milk laden cans are received at the dairy, the milk is removed, and both the empty cans and their covers should be thoroughly washed and sterilized before the covers are re-applied to the cans and the assembled containers are returned to the producers or otherwise re-utilized. In dairies where large quantities of milk cans are thus treated, the cans and covers are preferably emptied in rapid succession with automatic machinery, and the successive cans and covers are thereafter cleansed automatically, after which the covers should be quickly re-applied to the receptacles. While the prior machinery for effecting automatic washing, sterilizing and drying of the succession of milk cans and covers, is quite satisfactory, considerable difficulty has heretofore been encountered in re-applying the covers to the containers, especially when the successive receptacles were not all of the same capacity, shape or size. Most of the prior cover replacers involve relatively complicated power driven mechanism which besides being expensive to install and operate, is rather unreliable in action, and these previous devices could not be readily applied to standard can and cover washers without excessive loss of time and considerable changing and expense.

It is therefore a more specific object of the present invention to provide an improved milk can cover replacer which obviates all of the objectionable features of prior devices of this kind, and which is extremely reliable in action.

Another specific object of my invention is to provide an automatic receptacle closure replacer especially adapted to reapply standard covers to milk cans or the like, and which is conveniently applicable as an accessory to standard can and cover washers.

A further specific object of the invention is to provide an improved mechanism for applying closure lids to containers advancing in succession along a definite path, and which is adapted

to automatically compensate for variations in the size and shape of the successive receptacles.

Still another specific object of this invention is to provide a new and useful can cover replacer which is operable by the successive cans to properly time the cover application and to accurately seat the successive covers in their receiving sockets.

An additional specific object of the present invention is to provide a very simple and durable receptacle cover applying mechanism, which is dependable in action, and requires minimum attention when in normal use.

Another specific object of the invention is to provide a milk can cover replacer especially applicable as an accessory to standard automatic straight-line washers, and which can be manufactured, installed, and safely operated at moderate cost.

A further object of my invention is to provide mechanism for applying washed and sterilized covers to clean cans, in a sanitary manner and without danger of damaging the elements.

These and other specific objects and advantages of the invention will be apparent from the following detailed description.

A clear conception of an embodiment of the invention, and of the mode of constructing and of applying and operating milk can cover replacers built in accordance with the improvement, may be had by referring to the drawings accompanying and forming a part of this specification in which like reference characters designate the same or similar parts in the various views.

Fig. 1 is a side elevation of an improved milk can cover applying mechanism, showing the same associated with the delivery end of a standard can washer;

Fig. 2 is a vertical section through the mechanism of Fig. 1, looking toward the can actuated and cover release elements of the assemblage;

Fig. 3 is a top view of the mechanism, showing a cover rolling by gravity toward cover applying position;

Fig. 4 is a somewhat diagrammatic perspective view of the improved mechanism, showing a cover in position ready for delivery thereof to a can advancing therebeneath; and

Fig. 5 is a perspective view of a commercial machine, showing a cover being applied to an advancing can.

While the invention has been shown and described herein by way of illustration, as being applied to a standard straight-line milk can washer of the type wherein the cans are inverted while being cleansed, and are righted automatically at the delivery end of the washer; and has also been disclosed as being operable by contact with lower portions of the successive cans, it is

not my desire or intent to thereby unnecessarily restrict the scope or utility of the improvement.

Referring to the drawings, the standard straight-line automatic milk can and cover washer and sterilizer comprises in general an intermittently movable straight-line endless conveyor 8 mounted upon a main frame 9 and being adapted to transport milk cans 10 of various sizes in succession through an enclosing housing 11 and past a series of spray nozzles for delivering 10 washing and sterilizing fluids against the cans; an independent conveying and washing assemblage for simultaneously transporting the successive can covers 12 through the housing 11; and mechanism 13 for inverting or righting the 15 previously inverted cans 10 and for delivering the same in succession upon a runway 14 carried by an extension 15 of the frame 9. The construction and operation of these automatic straight-line washers, is well known, and forms no essential part of the present invention. 20

The improved can cover replacer constituting my invention, comprises generally a pair of upright shafts 16 journalled in upper and lower bearings 17, 18 respectively mounted on the washer frame 9 at opposite sides of the runway 14; lower longitudinally adjustable can actuated arms 19 rigidly secured to the pivot shafts 16 near the lower bearings 18, and each having its swinging end directed inwardly toward the corresponding end of the other arm 19 and provided with a can engaging roller 20; upper shaft actuated gate arms 21 also rigidly secured to the shafts 16, near the upper bearings 17 and each having its swinging end directed inwardly toward the corresponding end of the other arm 21 and provided with an upwardly and forwardly inclined gate bar 22; a torsion spring 23 embracing each pivot shaft 16 intermediate the bearings 17, 18, and each having one end firmly attached to the adjacent portion of the frame 9 while its opposite end is likewise, but adjustably attached to the adjoining shaft 16 by means of a collar 24 and clamping screw 25; a fixed inclined cover rollway or guide 26 carried by the frame 9 and having its upper end in open communication with the cover runway 27 of the washer, while its lower open end is directed inwardly toward and above the can runway 14; a tiltable flat inclined cover slide or chute 28 disposed beneath and laterally adjacent to the guide 26 and being swingably suspended at its upper end from the frame 9 by means of a shaft or pivots 29, so that the lower end of the chute 28 may swing toward and away from the lower runway 14; a cover guiding hood 30 carried by the lower swinging end of the chute 28; and a counter-weight 31 carried by an arm 32 projecting upwardly and rearwardly from the upper end of the chute 28, and being cooperable with a fixed stop abutment 33 to limit the downward swinging motion of the chute.

Each of the can actuated arms 19 is preferably adjustable in length with the aid of bolts 34 carried by the outer arm sections and coacting with slots 35 in the inner sections, so as to change the relationship between the rollers 20 and the gate arms 21 to compensate for variations in the speed of operation of the machine; and the arms 19 may be caused to coact with stop plates 36 in order to limit their inward swinging motion. The arms 19 may also be secured to the pivot shafts 16 anywhere above the lower bearings 18 so as to cause the rollers 20 to engage the successive advancing cans 10 at any desired point, and the

collars 24 and screws 25 may obviously be utilized to secure any desired tension in the springs 23. These springs 23 should be formed to constantly urge the lower arms 19 toward the stop plates 36, and to maintain these arms against the stops when no cans 10 are engaging the rollers 20. The counterweight 31 may also be made adjustable along the arm 32 in order to properly counter-balance the weight of the chute 28 and hood 30. The entire can cover replacing assemblage may obviously be applied as an accessory to either new washing machines, or to machines already installed, by merely providing a supporting extension 15 therefor to the main frame 9, and final can discharge guides 37 may also be provided along the runway 14.

During normal operation of the washer and can cover replacing assemblages, after the cover replacer has been properly installed and adjusted, it will function to automatically place a cover 12 on each milk can 10 as the latter are discharged in succession from the washer housing 11. The main conveyor 8 will normally transport the cans 10 in inverted condition and in succession through the housing 11, and the can covers 12 will be simultaneously transported in the position shown in Fig. 3 along the washer guideway 27. The successive clean cans 10 upon leaving the housing 11, are righted and deposited in upright position upon the runway 14, along which they may be transported either by succeeding cans 10 or by other conveying means. As the successive covers 12 emerge from the guideway 27 and are deposited in the rollway 26, they roll by gravity downwardly toward the inclined chute 28 and are eventually deposited flatly thereon. The inertia of the downwardly advancing successive covers 12 carries them downwardly along the chute 28 beneath the hood 30 where they are momentarily stopped by the upper gate arms 21 and inclined bars 22. The corresponding advancing can 10 thereafter engages the rollers 20 and spreads the lower arms 19 apart, and in so doing, the shafts 16 are rotated in the bearings 17, 18 and simultaneously spread the upper arms 21 and gate rods 22 apart. As this spreading action proceeds, the springs 23 will be subjected to increasing torsion, and the spreading movement will ultimately be sufficient to permit the cover 12 to pass between the bars or rods 22, and to drop by gravity into the receiving socket of the can 10 as illustrated in Fig. 5. Each of the advancing cans 10 thus automatically picks up a properly positioned cover 12, and the rollers 22 continue to ride along the trailing curved rear wall of each can 10 and permit the springs 23 to become effective to quickly restore the lower actuating arms 19 and the upper gate arms 21 to normal position, as shown in Fig. 3.

When the successive cans 10 are relatively low height as depicted in the drawings, and are insufficiently tall to contact the cover chute 28, this chute will not swing about its pivot shaft 5 29, but will remain in the position shown in Fig. 1 with the counterbalancing weight 31 in contact with the stop 33. However, if a higher can 10 is advanced along the runway 14 and beneath the chute 28, the upper portion of the high can 0 will contact the bottom plate 38 of the cover chute 28, and will swing this chute upwardly about its suspension pivot 29 sufficiently to permit the can 10 to advance forwardly beneath the 5 chute 28. During such upward displacement of the lower delivery end of the chute 28 by a tall

can 10, the counter-balancing weight 31 will be lowered away from the stop 33, but after the high can has passed the chute 28 and has been supplied with a cover 12, the weight of the chute 28, hood 30, and plate 33, which exceeds that of the counter-weight 31 and arm 32, will again return the counter-balancing weight 31 and the chute 28 to the position illustrated in Fig. 1. The can actuated cover replacer thus functions automatically to apply covers 12 to cans 10 of various height or size, within the limits of the space provided by the frame, and the stop 33 may also be made vertically adjustable so as to insure proper cooperation of the cover supply chute 28 with cans 10 of different heights.

From the foregoing detailed description, it will be apparent that my present invention provides an improved can cover applying assemblage which is extremely simple, compact and durable in construction, and which is moreover highly efficient in operation. By virtue of the fact that the improved mechanism is operated directly by the advancing cans 10, and no special power driven connections are necessary, the cover replacer may be readily applied as an accessory to various types of old or new can washers, and is adapted to be actuated at minimum cost. The present improved can cover replacer is positive and entirely automatic in action, and also automatically adjusts itself for cooperation with cans of various sizes; and while the improved assemblage is shown herein as being associated with a can washer of a particular type, it may obviously be applied wherever it is desired to apply closures to advancing receptacles in succession. My improved milk can cover replacer applies the covers to the cans in a safe and sanitary manner without necessitating manual handling of the cover or can, and has proven highly satisfactory and successful in actual commercial use. It is intended that the word cover as used herein shall designate any kind of closure for an opening in a receptacle, and that the word can as specifically used shall include any type of container or receptacle.

It should be understood that it is not desired to limit this invention to the exact details of construction, or to the precise mode of operation, herein shown and described for various modifications within the scope of the appended claims, may occur to persons skilled in the art.

I claim:

1. In combination, guide means for conducting cans along a definite path, means for feeding covers to a definite zone above said path, a vertical pivot shaft disposed on each side of said path, a can actuated arm associated with each of said shafts and extending into said path adjacent to the lower body portion of the cans, and a gate arm associated with each of said shafts above said path and extending inwardly in front of said cover feeding means, said gate arms being operable by the advancing cans through said shafts and said actuating arms to release the successive covers from said feeding means.

2. In combination, guides for conducting open topped milk cans along a definite rectilinear path, a cover supply chute swingable about a horizontal axis toward and away from said path, vertical pivot shafts disposed on opposite sides of said path, gate arms carried by upper portions of said shafts and extending inwardly in front of the delivery end of said chute, and actuating

arms secured to the lower portions of said shafts and extending inwardly into the path of the lower body portions of the advancing cans.

3. In combination, guides for conducting open topped milk cans along a definite rectilinear path, a cover supply chute swingable about a horizontal axis toward and away from said path, vertical pivot shafts disposed on opposite sides of said path, gate arms carried by upper portions of said shafts and extending inwardly in front of the delivery end of said chute, actuating arms secured to the lower portions of said shafts and extending inwardly into the path of the lower body portions of the advancing cans, and spring means for constantly urging said arms inwardly.

4. In combination, guides for conducting open milk cans along a definite path, a cover supply chute swingable about a transverse fulcrum toward and away from said path, pivot shafts disposed on opposite sides of said path, gate arms carried by corresponding end portions of said shafts remote from the cans and extending inwardly in front of the delivery end of said chute, and actuating arms carried by the opposite end portions of said shafts and extending inwardly into the path of the body portions of the advancing cans.

5. In combination, guides for conducting open milk cans along a definite path, a cover supply chute swingable about a transverse fulcrum toward and away from said path, pivot shafts disposed on opposite sides of said path, gate arms carried by corresponding end portions of said shafts remote from the cans and extending inwardly in front of the delivery end of said chute, actuating arms carried by the opposite end portions of said shafts and extending inwardly into the path of the body portions of the advancing cans, and spring means coacting with said shafts to constantly urge said arms inwardly.

6. In combination, guide means for a succession of advancing cans, a cover supply chute above said guide means, said chute including means movable by the advancing cans to cause said chute to properly cooperate with the open ends of cans of different height, a pair of gate arms pivotally suspended on opposite sides of said guide means and cooperating with the cover delivery end of said chute, a pair of can actuated arms pivotally suspended on opposite sides of said guide means, and means connecting said can actuated arms to said gate arms for periodically swinging said gate arms to release the successive covers as successive cans actuate said can actuated arms.

7. In combination, guides for conducting open topped milk cans along a definite rectilinear path, a cover supply chute swingable about a horizontal axis toward and away from said path, vertical pivot shafts disposed on opposite sides of said path, gate arms carried by upper portions of said shafts and extending inwardly in front of the delivery end of said chute, and actuating arms secured to the lower portions of said shafts and extending inwardly into the path of the lower body portions of the advancing cans, said chute including means cooperable with the upper ends of the successive cans to swing the chute about said axis for proper coaction with cans of different heights.

NORMAN GRAN.
